Leonard Norcross Dixfield Maine

Letters Patent June 14. 1834. 8255x

The Schedule referred to in these Letters Patent and making part of the same containing a description in the words of the said Leonard Norcross himself of this improvement in an impervious Elastic air refreshing Water Dress.

To all to whom these presents shall come.

Be it known that I Leonard Norcross of Dixfield in the County of Oxford State of Maine have invented a new and useful improvement in an impervious Elastic air refreshing Water Dress, and that the following is a full and exact description of the construction of the invention and operation as invented by me. Specification of my impervious Elastic Air refreshing Water Dress, to be used in skating for and regaining property lost in rivers bays harbors &c described in these prints.

1st The Dress for the body. It is the cap or covering for the head.
2nd The breathing nose. 1st The dress for the body is composed of India rubber, India Rubber cloth, Cloth, printed in a suit garment of leather, varnished with India Rubber or printed with India Rubber paint and varnished with India Rubber varnish, and is formed to fit the feet legs, chest, shoulders arms and hands as close as may be and admits a dress of leather under it and gives the person who wears it ease of motion to walk, stoop and to move the arms and hands. This may be made entirely whole except an aperture at the neck to receive the head dress or cap. When composed of natural legs elastic than India Rubber it will be necessary to have a larger opening at the neck and folded on the back of the neck to bring it closer around the cap and is varnished and made light as described in part. 2nd on the cap and upper part of the stock may be made together and this upper and lower parts of the dress be brought together two loops around the neck which is forced together by a belt with buckle, the belt passing through both loops. 3rd 3rd the cap or head dress may be made of glass, leather wood or any suitable

W.H.

mettalic substrings. It should be of such a size as not to press upon any part of the head and fall into rest upon the shoulder. It should be round at the neck with two projections round it over the lower part with a groove or concave between them over which the drop is brought and passed into the groove by two half circles formed of copper or iron with a joint in the fore part made closed and drawn tight by a screw by hand. There must be a glass placed in the cap before the eyes when not composed of the materials of sufficient size to assist the sight in the various manoeuvres - ³³ The breathing hose one will answer in a small depth of water and must be of larger bore than when the crew use it. They may be constructed similar to breathing hose. When two are used one is to move the rudder, the other the discharger and are of about half an inch bore. Their length must be at least equal to the depth of water in which they are used. The rudder is introduced through cap or upper part of the drop so as to discharge the air against the mouth and nostrils. The discharger must be introduced in a convenient position as may be to discharge or carry off the air which has been exhaled they are coupled together from the cap upwards to their length and should have a chain between them of sufficient size to counteract their buoyancy & for other purposes. There must be a weight of heavy metal attached to the drop and cap to counteract their buoyancy. The most convenient manner of using this drop will be to have a cylinder of sufficient size and length to wind this hose and chain upon attached to the vessel boat or raft the rudder passing from the surface of the cylinder into the shaft of it near one end which must have a hole in at the end connecting with that in the hose. There may be introduced into the end of the shaft a tube with valves and piston or a forcing air pump or something in the form of a bellows which do not interfere with the cylinder. The tube or hose of the bellows may pass into the end of the shaft in a lining of soft leather or cork to make an airtight joint and the shaft valves while they are stationary. This will facilitate the necessary object of keeping a free current of air to the person within the drop at any depth of water

and while descending and ascending. When this dock is used, in situations exposed to storms &c. a coarse wire grating in the form of a bell may be used and suspend near the bottom so as to be raised ~~to be removed~~ by the diver at pleasure. Holes about the body may be used to prevent the pressure of the water being injurious. A man in this dock can descend to a great depth and remain there for hours moving under the cabin or hold of vessels which are sunk, walk about upon the bottom, make rigging fast to whatever is to be raised, handle a bar of iron to considerable advantage, remove with those at the surface by putting them in near the discharging hose and speaking in this same and plausibly lowered down for the foundation of abutments of bridges &c. - Lamps may be used under water by the operator by making use of the heat the respiration entering the bottom of a glass cylinder another hose the top. - A lamp placed in the head dock in right will cause a brisk circulation of air through the hose.
